(57) **CLAIM**

The ornamental design for a door handle as shown and described.

DESCRIPTION

FIG. 1 is a perspective view taken from a top, front, left side of a door handle according to our design, shown on a vehicle illustrated in dashed lines;

FIG. 2 is a perspective view taken from a top, front, right side thereof;

FIG. 3 is a perspective view taken from a top, rear, right side thereof;

FIG. 4 is a perspective view taken from a top, rear, left side thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof;

FIG. 10 is a bottom plan view thereof;

FIG. 11 is a perspective view taken from a top, front, left side of the door handle according to our design;

FIG. 12 is a perspective view taken from a top, front, right side thereof;

FIG. 13 is a perspective view taken from a top, rear, right side thereof;

FIG. 14 is a perspective view taken from a top, rear, left side thereof;

FIG. 15 is a front elevation view thereof;

FIG. 16 is a rear elevation view thereof;

FIG. 17 is a right side elevation view thereof;

FIG. 18 is a left side elevation view thereof;

FIG. 19 is a top plan view thereof; and,

FIG. 20 is a bottom plan view thereof.

Throughout the Figures, where shown, the dashed broken lines shown in the drawings are for the purpose of illustrating portions of the article and form no part of the claimed design and the dot-dash broken lines define the bounds of the claimed design and form no part thereof. The dashed lines showing portions of the vehicle are for illustrative purposes only and form no part of the claimed design.

1 Claim, 20 Drawing Sheets
